VENTILATOR

George R. Siefken, New York, N. Y.

Application April 17, 1939, Serial No. 268,212

6 Claims. (Cl. 98—95)

This invention relates to ventilating apparatus for use in homes, office buildings, and other similar structures and is more particularly concerned with a novel device by which atmospheric air may be admitted to the structure in automatically regulated amounts and distributed in such a way as to promote circulation within a room, but without development of drafts. These effects are obtained by controlling the entering air stream and causing it to be diffused, so that the course taken by the air is that naturally resulting from the manner of admission and influence of gravity upon it.

This application is a continuation-in-part of my copending application Ser. No. 150,915, filed June 29, 1937.

The new ventilator is especially adapted for installation in an ordinary window frame without the necessity of alterations, although in new structures, it may be built into the wall as a permanent feature. In either case, it is preferably disposed above a heater, such as a radiator, so that in cold weather, the incoming air stream and the current of air rising from the radiator may be intermingled and properly diffused and distributed.

The apparatus of the invention includes a housing having an inlet opening, through which outside air may enter, and the opening preferably extends substantially the full length of the housing and admits the air in a generally horizontal direction after which the air turns and flows upwardly into the room through orifices controlled by differentially weighted valve members. As variations in the velocity of the outside air occur, the stream entering the housing causes more or less of the valve members to be held against their seats in closed position and the amount of air admitted into the room is thus automatically controlled. The valves are preferably arranged in a group consisting of two rows and the ends of the rows are spaced inwardly from the ends of the housing so that the streams issue from the valves inwardly from the side members of the window frame, when the device is mounted in the frame or built into the wall below the frame. Above the valve openings is a deflector which is longer and wider than the group of valves and may be tilted to different positions in which it engages the housing either forwardly or to the rear of the group of valves. In the first position, the entering air stream is caused to flow upwardly along the wall or window pane and this adjustment is employed in winter so that the rising stream of air from the radiator blankets the cold air enter-

ing. As the cold air tends to turn and flow downwardly under the force of gravity, it is intermingled with the rising stream of warm air, and cold drafts are thus prevented. In the summer, when the window pane is warm because of being heated, for example, by the sun, the deflector is turned to the second position in which the entering air is directed away from the pane and into the room so that the cooler outside air may not be heated by its travel along the warm pane. 10

In the group of valves, the weighting used is such that with low wind velocities, for example, up to four miles an hour, all of the valves are open. As the velocity increases, the valves are successively closed until ultimately only one or 15 two valves may be open. The high velocity air enters the room through these valve openings somewhat in the nature of jets and proper diffusion is more difficult than in the case of the low velocity streams. Accordingly, to insure such 20 diffusion, the valves are so arranged that those of the heaviest weighting lie in the middle of the group, with the heaviest valves preferably lying in the row farther from the window. With this arrangement, a relatively high velocity air 25 current entering the room strikes the middle of the deflector and is directed against the middle of the window-pane. The air is thus directed in a stream located inwardly from the edges of the current of hot air rising from the radiator 30 and cannot escape at the edges of the hot stream and turn directly downwardly into the room. Instead, it rises with the hot current a distance depending upon the outside wind velocity and thus becomes thoroughly intermingled with and 35 diffused through the hot air. Drafts are, accordingly, prevented.

For a better understanding of the invention, reference may be had to the accompanying drawings in which

Fig. 1 is a front elevational view of one form of the apparatus, with parts broken away;

Fig. 2 is a transverse sectional view of the apparatus on an enlarged scale;

Fig. 3 is a plan view showing the valve members 45 of the apparatus, and

Figs. 4 and 5 are enlarged sectional views on the lines 4—4 and 5—5, respectively, in Fig. 3.

In the construction illustrated, the apparatus comprises a housing 10 mounted in a window 50 frame upon the sill 11 above a heater shown as a radiator 12, and when the window is opened partially, a part of the ventilator is exposed to the outside air. The housing contains an intake chamber 13 provided with an entrance opening 55

- 14 at the rear, the chamber being preferably rectangular and extending across the sill the entire width of the window. In some cases, it may be advantageous to provide cooling coils 15 in the 5 intake chamber, to cool the incoming air and, if desired, a filtering screen 16 may be installed in the chamber so that the air entering the chamber will pass through it and be filtered before entering the room. The screen 16, as shown, includes a fabric 17 stretched over rods 18 within a metal frame 19, the frame being mounted to slide into and out of the chamber in the manner of a tray so that it may be easily removed through one end of the housing for cleaning. 10 15 Along its front edge, the frame 19 bears against a felt pad 20 secured to the housing, and at the rear, the frame is engaged on top by another felt pad 21 which is held between the double walls 22 of the housing and projects outwardly beyond the 20 edges of the walls.

In order to prevent entrance of air through the window above the device, a flexible rubber loop 23 extending the width of the device is mounted on the top thereof to project out to 25 the rear, and when the sash is raised, the loop bears against the sash, so that air cannot enter the room except through the device. The loop 23 may be secured to the housing by a releasable clamp 24, so that it may be readily replaced 30 when worn.

- The top 26 of the housing has a group of openings 27 through which air from the intake chamber passes into the room and these openings preferably lie outwardly from the end walls of 35 the housing so that the current of air entering the housing converges before passing through the openings. The quantity of air passing through the openings is controlled by automatic mechanism which, as illustrated, includes a series of 40 valves 28 fitting into the openings which are arranged in two rows lengthwise of the housing. Each valve is in the form of a truncated cone, with its smaller diameter at the top, and it is mounted for movement on a vertical stem 29 projecting upwardly through the corresponding opening, the stems being supported on bars 30 attached to the housing end walls. The valves are of light weight so that they may be raised to close the openings 27 by air entering the chamber 13, and the weighting is differential so that when the pressure of the entering air increases, the valves will be closed in succession, and as the pressure of the air decreases more and more valves will open. In this way, the air entering 50 55 the room is automatically regulated in amount, regardless of outside wind conditions. The valves seat against the edge 27' of the openings in a layer of felt 26' which is held between double walls forming the top 26.
- 60 The weighting of the valves 28 is such as to provide the incoming air with a predetermined flow characteristic to be described, and to this end I prefer to arrange the valves as shown in Figs. 3, 4, and 5. As there shown, the valves of 65 different weights are designated by different numbers from 1 to 6, the weights increasing as the numbers increase. It will be observed that the valves in each row or series offer progressively greater and then less resistance to closing from one end of the series to the other, since the heaviest valves are near the middle of the series. Also, the heaviest valves are in the series which is farther from the window. As a result, air streams of the higher velocities enter 70 75

the room inwardly from the ends of the housing and the highest velocity streams enter through valves in the front row.

In ventilating rooms in cold weather, the cold entering air must be thoroughly diffused in order that cold drafts may be prevented, and provision must be made to prevent the cold air from flowing directly to the lower levels of the room. Accordingly, the ventilator is preferably placed above a radiator and the entering air flowing 10 upwardly from the valves is caused to be blanketed by the warm air current rising from the radiator. In this way, the heavier cold air cannot turn and flow downwardly except through the rising warm air, and diffusion and thorough 15 intermingling of the fresh air from the outside and the air within the room are thereby accomplished. When the weather is warm, the window pane may be highly heated by the sun shining directly upon it and, in that situation, the entering air should be kept away from the window so that it will not be warmed by heat from the glass.

To control the flow of the entering air, the ventilator is provided with a deflector 33 mounted on horizontal pivots on upright members 34 attached to the top 26 of the housing beyond the ends of the group of openings 27. The deflector, which may be formed of a plate stiffened by a rib 35, extends substantially the whole 30 width of the apparatus and may be operated to deflect the air issuing from the openings 27 either along the window or away from it, as desired.

In the operation of the apparatus illustrated, 35 the current of atmospheric air entering the intake chamber converges as it approaches the openings 27 and flows upwardly and into the room in controlled amounts through the valves. The air issuing from the openings strikes the 40 deflector and the several streams are spread out laterally and intermingled so that the fresh air flows into the room in a thin, wide stream. When the weather is cold, the deflector is placed in the position illustrated in Fig. 2, in which position it directs the fresh air stream upwardly 45 along the window. The rising current of hot air from the radiator then flows upwardly on the room side of the cold air stream, blanketing the latter and preventing its turning and flowing toward the floor except by passage through the hot air. In this way, the fresh air is tempered and thorough diffusion obtained.

When the outside wind velocity is relatively high, the entering air is admitted through the 55 ventilator inwardly from the edges of the blanketing current of hot air and cannot escape at the sides. It thus flows upwardly to a substantial height in contact with the current of heated air, the height to which the entering air rises depending on the outside velocity. The streams of greatest velocity are those most thoroughly blanketed, this result following from the central position of the valve openings through which such streams are admitted. Such high velocity 60 streams are also kept from contact with the window frames which, in the case of modern buildings, are frequently made of metal and are quite cold in the winter time.

When the weather is warm and the sun is 70 shining upon the window and has heated the glass, it is desirable to keep the fresh entering air from coming in contact with the window pane so that it will not be heated by the hot glass. For this purpose, the deflector is tipped to the 75

dotted-line position shown in Fig. 2 and when so placed, the deflector directs the entering air into the room away from the window.

I claim:

5. 1. A ventilator for admitting air into a room over a heater comprising an intake chamber having an opening for admitting air from outside, means for controlling the passage of air from the intake chamber to the room including a series 10 of valve members serially movable to closed positions by increased velocity of the air admitted from outside, the valve members at the ends of the series being movable to closed positions by a smaller velocity of air than those between the 15 ends of the series, whereby said members are operable to cause a stream of air issuing into the room to fan out with the greatest rate of flow at the middle portion of the stream.
2. A ventilator for admitting air into a room 20 over a heater comprising an intake chamber having an opening for admitting air from outside, means for controlling the passage of air from the intake chamber to the room including a series of valve members movable toward closed positions by air admitted from the outside, the valves 25 offering progressively greater resistance to closing from each end toward the center of the series, whereby said members are operable to cause a stream of air issuing into the room to fan out 30 with the greatest rate of flow at the middle portion of the stream.
3. A ventilator for admitting air into a room over a heater comprising a housing disposed adjacent a wall of the room and having an intake 35 chamber with an opening for admitting air from outside, means for controlling the passage of air from the intake chamber to the room including valve members arranged in two transversely spaced series generally parallel to the wall and 40 serially movable to closed positions by increased velocity of the air admitted from outside, the valve members at the ends of each series being movable to closed positions by a smaller velocity of air than those between the ends of the series, 45 and at least one of the valve members in the series at the greater distance from the wall offering greater resistance to closing than any of the valves in the other series.
4. A ventilator for admitting air into a room 50 over a heater comprising an intake chamber having an opening for admitting air from outside,
- means for controlling the passage of air from the intake chamber to the room including a series of valve members serially movable to closed positions by increased velocity of the air admitted from outside, the valve members at the ends of the series being movable to closed positions by a smaller velocity of air than those between the ends of the series, and a deflector in the path of the air issuing from the valves for spreading out and directing the flow of air into 10 the room.
5. A ventilator for admitting air into a room over a heater comprising a housing disposed adjacent a wall of the room and containing an intake chamber having a generally horizontal, elongated opening extending substantially the entire length of the housing for admitting air from the outside, means for controlling the passage of air from the intake chamber to the room including a series of valve members serially movable to 15 closed positions as the velocity of the air admitted from the outside increases, said control means also including outlet means arranged along the top of the housing generally parallel to said wall and spaced inwardly from the ends of the 20 housing to cause the current of air entering said opening to converge before passing through the outlet means, and a controllable deflector in the path of air issuing from said outlet means, the deflector extending beyond the ends of the outlet 25 means and being operable to spread out and direct the flow of air into the room.
6. A ventilator for admitting air into a room over a heater comprising a housing disposed adjacent a wall of the room and having an intake 30 chamber with an opening for admitting air from the outside, means for controlling the passage of air from the intake chamber to the room including a series of valve members serially movable to closed positions as the velocity of the air admitted from the outside increases, and a deflector 35 pivoted in the path of air passing through the valves into the room and having deflector portions extending on each side of its axis, the deflector being movable to different positions substantially into engagement with the front and back of the housing, respectively, to form with the housing an elongated opening to direct air issuing from the valves either along said wall or 40 away from the wall.

GEORGE R. SIEFKEN.
